LIFE PRESERVER

Frederick Lee Brown, Greenfield, Ohio, assignor
to The American Pad & Textile Company,
Greenfield, Ohio, a corporation of Ohio

Application October 30, 1939, Serial No. 302,049

8 Claims. (Cl. 9—20)

The present invention relates to a device for the saving of lives and more particularly to preservers to be worn by persons whose occupations and recreations impose upon them the hazard of drowning.

The greatest number of these life preservers are of the vest type and are intended for continuous wearing over long periods of time when the wearer is actively using his or her body. In building such a preserver, as distinguished somewhat from the preservers which have a large bulk of buoyant material around the head such as those used in sports like racing, there is a balance of expedients between the inconvenience upon one hand, of having a cumbersome bulk of buoyant material located at any one point upon a user's body to provide a centralized center of buoyancy, and, upon the other hand, spreading the buoyant medium throughout a preserver garment as thinly as possible for the wearer's comfort and convenience. The resulting garment is one covering a wide area of the body down as far as a wearer's hips.

Although this balance of expedients does away with any great amount of bulkiness at any given point and has many advantages both as to warmth and protection from personal injuries, the center of buoyancy afforded by the jacket as a result is quite low upon the wearer's body.

The location of the center of buoyancy is very important. A life preserver having a low center of buoyancy has a tendency to lift the body of the wearer out of the water far enough to cause the wearer to tip forwardly or backwardly, the low center of buoyancy imposing upon the preserver a tendency to support the wearer horizontally, rather than vertically.

In the present invention, I provide a life save vest wherein the bulk of the life saving material is spread as thinly if not more thinly over the wearer's body than conventionally, yet provides a high center of buoyancy when the wearer is in the water so as to keep the wearer erect without tipping, with the wearer's head and shoulders out of the water.

In addition to the low center of buoyancy present with conventional life preservers, the conventional life preservers do not permit ready access to pockets and full freedom of activity in sitting and climbing.

In this connection, a further object of the invention is to provide a life save vest which affords no inconvenience to a wearer using his arms for work or play and does not hinder quick access to the pockets on his regular clothing or

cause discomfort when he sits down or climbs a ladder.

In certain particulars it is also within the intention of the present invention not only to provide a life save vest which affords ready access to pockets when the wearer is out of the water, but also frees the wearer of any restraint with regard to his pockets and the movement of his body when the wearer is in the water.

10 More particularly, one of the purposes of the present invention is to provide a life preserver wherein the lower part thereof folds upwardly to shift or raise the center of buoyancy to a point proximate the chest and shoulders of the wearer when the wearer is in the water.

15 Another object of the invention is to provide a life preserver which automatically changes its center of buoyancy when a wearer enters the water, and, as a corollary thereto may be arranged to shift the center of buoyancy any distance vertically, or if need be, in any other direction desired.

20 A further object of the invention is to provide a life saving device of the class described which is simple in construction, easy to manufacture, and which can be quickly put on and taken off by the wearer in event quick action is necessary.

25 These being among the objects of the present invention, other and further objects will become apparent from the drawings herein, the description relating thereto and the appended claims.

30 Referring now to the drawings:

35 Fig. 1 is a side perspective of a preferred form of the invention as it appears when fastened upon a user;

Fig. 2 is a rear view of the life preserver illustrated in Fig. 1;

Fig. 3 shows the life preserver shown in Fig. 1 when it is unfolded and flattened with the outside surface up;

40 Fig. 4 is a section taken upon the lines 4—4 in Fig. 3;

Fig. 5 is a view similar to Fig. 1 showing another embodiment of the invention;

45 Fig. 6 is a rear view of the life preserver illustrated in Fig. 5;

Fig. 7 shows the life preserver illustrated in Fig. 1 when it is unfolded and flattened with the outside surface up;

50 Fig. 8 is a section taken upon the lines 8—8 in Fig. 7;

Fig. 9 is a diagrammatical view illustrating the shape assumed by the preferred embodiment of the invention when the wearer is in the water; and

Fig. 10 is a view similar to Figs. 3 and 7 illustrating another form of the invention.

In practicing my invention, I prefer to provide a life preserver garment in which the buoyant material is spread throughout its length and breadth and either eyeletted, quilted, stitched or tufted in place in a manner so that a portion of the garment moves upwardly to shift the center of buoyancy upwardly when the wearer enters the water as compared with the center of buoyancy as it exists when the wearer is out of the water.

Referring now to the drawings in further detail, the life preserver illustrated in Figs. 1, 2, 3 and 4 is constructed to be worn as a jacket, a name by which the preserver 10 will be referred to hereafter. The jacket 10 is made of two thicknesses of strong, preferably closely woven fabric comprising an inner layer 11 and an outer layer 12 (see Fig. 4) which are stitched together around the edges as at 13 to form an envelope 14 that is cut to a pattern having two armholes 15.

Intermediate, and, preferably vertical lines of stitching 16 are made in the upper portion of the envelope to provide downwardly opening tubes 17 located around the chest and shoulders. The tubes 17 are spaced and arranged for comfort, and to permit full movement of the user's arms. The lines of stitching 16 under the armholes 15 are spaced widely to provide an expanse of loose fabric, as at 20, which will fold upon itself without discomfort when the jacket is put on and fastened in place by the wearer.

Any approved buoyant material, such as balsa wood, cork or rubber may be used to fill the tubes 17 although I prefer to use, and have shown throughout the several views the use of a fibrous material 21 known as kapok.

The kapok 21 is stuffed into the tubes 17 from the lower ends 22, after which the tubes are closed by a line of stitching 23, which, as shown in Fig. 3, is made horizontally around the jacket at a point near or slightly below the middle of the jacket.

In this particular embodiment of the invention, a second line of stitching 24 is made parallel to and about an inch below the first line of stitching 23. This provides a band or web of material 25 connecting the upper portions 18 and lower portion 19 of the jacket so that the lower portion is free to move and swing about the web 25 from a depending position, as shown in Figs. 1 and 2, to a position proximate the upper portion 18, as shown in Fig. 9, where the wearer is shown in the water.

After the two stitched lines 23 and 24 are made, I add lines of stitching 26 in the lower portion 19 of the jacket to form tubes 27 therein. Although the tubes 27 may be disposed vertically I prefer to have them horizontal so that the lines of stitching 26 between them provide horizontal bend lines assisting in an upward flexing of the lower portion 19 when, upon occasion, the lower portion is folded back upon the upper portion 18.

In view of the fact that the jacket is wrapped around the wearer's body and thereby assumes a curvilinear contour difficult to bend horizontally I sever the lower portions into four parts along three vertical cuts extending from the bottom edge 28 of the jacket to the line of stitching 24. Two of these lines of severances 29 are located under the armholes 15 and the other line of severance, 30, is in the middle of the back.

The lines of severances 29 may comprise cuts

which need not have any width or, as preferably shown in the several views, comprise substantial U-shaped cuts 31 in which a substantial amount of material is removed from the loose expanse of material 20.

All of the tubes 27 are closed by stitching along one boundary of severance and are open along other boundaries of severance. The kapok is stuffed into tubes 27 at their open ends, after which the open ends are closed by stitching, thus completing the jacket insofar as providing it with a buoyant material.

The requirements and tests prescribed by the Government for life preservers offered for sale to the public at large are concerned almost exclusively with the amount of buoyancy present in a preserver, the ruggedness of the material used for buoyancy and the fastenings by which the preserver is secured to the user.

In the present invention, these requirements are fully complied with. The jacket, just described, receives the full quota of kapok necessary to meet the requirements and whether the kapok is stuffed in tubes made in an envelope as described or whether the kapok is secured to the jacket as an independent assemblage it is immaterial except insofar as the appearance and expediency of manufacturing are concerned.

The several tubes illustrated and described may receive cork or balsa wood or some other approved buoyant material. In event, however, there is not enough tubular capacity for any given quota of buoyant material, other tubes may be added along the lower edge of the jacket.

In this connection, it may be well to point out at this time that I prefer to add tubular capacity along the lower edge of the jacket in order to lessen the thickness of the kapok stuffing throughout the whole jacket. It is desirable to have the jacket as thin as possible for the wearer's convenience and this I can do in the present invention without encountering any further dangers of a further lowered center of buoyancy which would result if this was done with conventional constructions.

The more the kapok bulk is spread downwardly the greater will be the shifting of the resulting point of buoyancy when the wearer enters the water.

Moreover, the free flexing of the four lower portions of the jacket about the web 25 permits the lower portions of the jacket to yield freely to the movement of the user's legs when climbing or sitting. The two front lower portions slide freely out upon the thighs when the sitting posture is assumed.

In providing the jacket illustrated, the length of the jacket is determined by the average man's height so that the lower edge of the rear flaps barely reach the top of a seat when the wearer sits down. In this way the distribution of the kapok may be made very thin as compared with former jackets. Moreover, the fact that the rear flaps extend down to the top of the seat provides a padding for the back of the wearer from the top to the bottom of a seat back.

In addition to this the web 25 is well above the waist line in the preferred embodiment so that the user can reach his watch pocket or his hip pockets (not shown) without any trouble, either in or out of the water. Only in the case of the watch or handkerchief pockets need there be any movement of the jacket and, in these instances, out of the water the flaps are merely flipped by the hand as the hand is inserted into the respec-

tive pocket being reached. A further safety feature is also provided. The user has unhampered access to his belt buckle so that his trousers may be removed or kicked free when in the water.

In operation, whenever the wearer of the vest falls, jumps or dives into the water, the lower portions are no longer affected by gravity which heretofore kept them down against the body but immediately become buoyant units which seek to reach the surface of the water independent of any restraints except the web 25 which then becomes an anchorage by which the lower buoyant units assist in lifting the wearer's shoulders out of the water.

In view of the fact that the jacket 10 is designed for continuous wear out of the water when the user is at work or play, it will be noted further that very often, in conventional life preservers extending below the waist line, the body structure of the conventional preserver becomes strained and deformed in a way causing it to flare outwardly permanently at the bottom. In the present invention the free movement of the lower portion relative to the upper portion has the advantage of permitting the lower portion to cling closely to the body of the user yet the lower portion 19 will yield to strains and stresses without being permanently deformed thereby.

Referring now to the construction of the fastening means, any suitable or approved fastening means may be employed in the present invention. I prefer, however, to use tie tapes made of heavy webbing so that when the knots are once tied they will not come undone, under reasonable use, without the loose ends being intentionally pulled. As shown in Figs. 1 and 3, three pairs of tapes are employed, the top pair 34 of which is secured by cross stitched ends 35 to the front marginal edges 36 of the jacket near the top of tubes 17.

The two lower pairs of tapes 37 and 38 are end secured by cross stitching 39 to the back, top portion 18 of the jacket near the lower edge of the armholes 15 from whence they pass over the tubes 17 in the front portions and through loops 40 that are secured to the front edges 36 at spaced points below the tapes 34.

The lower tape 38, as best shown in Fig. 4, passes across the tubes 17 at or near their lower ends without in any way hindering the freedom of movement already described for the lower portion of the jacket. In event anybody desires to thread the lower tape 38 through the band 25, or in event the tape 38 will normally come to rest against the band 25 when tightened, it will be appreciated that the width of the band 25 may be increased or decreased as desired to maintain full freedom of movement upwardly of the lower portion 19 of the jacket.

Referring now to Figs. 5, 6 and 7, a construction for a life preserver is shown which is more of a dress style than the design of the preferred embodiment. In this particular construction, the line of fold 5 is a little lower and the amount of kapok bulk disposed below the line of fold is somewhat less. Moreover, the fold line is a single line of stitching rather than a web provided by a double line of stitching. In this construction, however, the vertical lines of severance under the armholes are of a depth sufficient to provide complete access to the wearer's pants pockets.

Although this embodiment is similar in structural details to the preferred embodiment just

described, the details are shown for purposes of illustration only, it being appreciated that for dress styles the outer layer of fabric 51 may be made of a decorative color or pattern with quilting disposed upon the inside thereof. Moreover, the tubes may be so constructed as to be opened at will, in which case removable kapok inserts may be used in order to allow the jacket to be laundered.

10 Referring now to Fig. 10, a construction is shown wherein the front portions are entirely severed at the waist from the rear portions of the jacket. In this instance, however, the lowermost strap 38 is threaded through the web portions 25 with enough extra width provided in the web to permit free upward movement of the front, lower portions unhampered by the presence of the strap 38. In this particular embodiment, the back is narrowed appreciably and the two rear lower flaps are not severed from each other, but move about the web 25 as a unit. A slight cutting away above the waist line at the back, as at 55, is provided to reduce the length of web 25 as much as possible so that its curvilinear contour assumed in following the back of a user, will not interfere with free movement of the rear flap portions upwardly. In this particular embodiment, more kapok is provided in the lower portion 19 in proportion to the upper portion 18 than in the other embodiments described. With this, the result is that the normal center of buoyancy out of water is unusually low, whereas when in the water, the center of buoyancy is proportionally higher.

35 Thus it will be appreciated that I have provided a life preserver wherein the bulkiness of buoyant material may be spread more thinly throughout a garment for the convenience of a user when worn constantly upon land, yet provides a raised center of buoyancy which prevents tipping of the user when in the water. Consequently, although a preferred embodiment and several modifications of the invention have been shown and described herein it will be apparent to those skilled in the art that various and further uses, modifications and changes may be made without departing from the spirit and substance of the invention, the scope of which is commensurate with the appended claims.

50 What I claim is:

1. A life preserver tailored to be worn as a vest comprising an envelope composed of an inner and outer layer of fabric stitched marginally together, intermediate lines of stitching providing tubular constructions disposed vertically in the upper portion and horizontally in the lower part of said envelope, a buoyant material of kapok inserted in said tubular constructions and two parallel lines of stitching securing the buoyant material in place in the upper portion and providing a web construction by which one part of said tubular constructions are movable into overlapping relation to another part of said tubular constructions.

65 2. A life preserver tailored to be worn as a vest by an adult comprising an envelope composed of an inner and outer layer of fabric stitched marginally together and cut on a pattern providing armholes, intermediate lines of stitching providing vertical tubular constructions in the upper part of said envelope and horizontal tubes in the lower part of the envelope, a buoyant material of kapok inserted in said tubular constructions and two parallel lines of vertically spaced stitching 70 securing the material in the vertical tubes and

providing a bend construction by which the tubular constructions in the lower part of the envelope are movable into overlapping relation to the upper tubular constructions about a plurality of fold lines.

3. A life preserver jacket tailored to be worn as a vest comprising a buoyant body portion disposed around the chest of a user below the top of the shoulders, fastening means for holding said body portion in place upon a user including a draw string at the waist, and freely movable independently acting separate body portions secured by fabric to and depending from the first named body portion below the waist of the wearer under the influence of gravity and flexing along horizontal stitch lines and said draw string to fold back upon and into overlapping contact with the first named body portion under the influence of buoyancy.

4. A life preserver characterized in connection with an adult of average size by two layers of fabric tailored to be worn as a vest comprising an upper buoyant body portion having buoyant material disposed around the chest of a user and held in place by lines of stitching cooperating to permit ready fitting of the body portion around the torso, fastening means for holding said body portion in place upon the user, a lower buoyant body portion divided into parts depending independently from the upper portion under the influence of gravity and each foldable back upon and against the buoyant material in the upper portion along a plurality of horizontally disposed vertically spaced lines of stitching under the influence of buoyancy in water.

5. A life preserver comprising a quilted envelope tailored to be worn as a vest and filled with thinly spread buoyant material, means for securing the envelope upon a person, and means for shifting the center of buoyancy of the buoyant material outwardly and upwardly with respect to the person when said person enters the water, including a lower portion comprising a plurality of separate and independently movable depending sections bounded and quilted by vertically spaced parallel lines of stitching to provide horizontal fold lines within the sections and between the sections and envelope, said envelope and sections being spaced vertically from each other when the sections are in hanging position and movable into overlapping position under the influence of buoyancy.

6. A life preserver characterized in connection with an adult of average size, comprising two spaced layers of fabric tailored to be worn as a vest, having a back portion and two front portions extending to a level below the waistline, said front portions being joined to the back portions by loose fabric intermediate arm holes in the upper part of the vest and notches over the side pants pockets of the wearer in the lower edge of the vest, buoyant material disposed between the layers in the upper part of the vest, means for securing the buoyant material in place including stitches predisposing the upper part to flex readily to follow the contour of the torso, buoyant material disposed between the layers in the lower part, means for securing the buoyant material

in place in the lower part including stitching arranged to allow the lower parts to flex upwardly without crushing the buoyant material when the wearer is sitting, and away from the body and up when the wearer is in the water, means for securing the free edges of the front portions together when the vest is put on including a strap fastened at one point to the back portion and free to draw with respect to the front portion at approximately the waistline between the upper and lower parts.

7. A life preserver characterized in connection with an adult of average size by two layers of fabric tailored to be worn as a vest with spaced lines of stitching joining the two layers to form tubular compartments, buoyant material in said compartments, said vest having a back portion and two front portions extending to a level below the waistline, means for securing the free edges of the front portions together when the vest is put on, said front portions being separated from the back portion by arm holes in the upper part of the vest and notches in the lower margins of the vest below the arm holes, which notches extend upwardly to a point proximate to the waistline, the stitching in the upper part of the vest comprising vertical lines of stitching extending from a point below the top of the vest to a point proximate to the waistline to provide flex lines permitting ready flexing of the vest between the compartments to follow the curve of the torso, there being sufficient loose fabric between the front and back portions to accommodate persons of varying girth, the stitching in the lower parts on each side of the notches comprising lines of stitching parallel with the waistline to provide flex lines permitting relative movement of the lower compartments without crushing the buoyant material in the compartments, said upper and lower parts being separated by stitching bringing the two fabrics close enough together to form a fold line approximately at the waistline so arranged that the upper and lower parts may fold substantially against each other without crushing the buoyant material in the compartments when the wearer sits down or is in the water.

8. A life preserver tailored to be worn as a vest comprising a jacket having a predetermined amount of buoyancy and including an upper buoyant body portion received around the ribs of the wearer below the top of the shoulders and a lower buoyant body portion divided into freely movable independently acting separate body portions secured by fabric to and depending from the upper body portion to a point below the waist of the wearer under the influence of gravity, fastening means for holding the body portions in place upon the wearer including an element for drawing the jacket against the body of the wearer at the waist, said element predisposing the upper edges of said separate body portions inwardly towards the body of the wearer and said separate body portions flexing along horizontally disposed stitch lines to fold back upon and into overlapping contact with said upper buoyant body portion under the influence of buoyancy.

FREDERICK LEE BROWN.
